LAMP

Gae Aulenti, Via dell'Annunciata 7, Milan, Italy

Filed Sept. 22, 1972, Ser. No. 291,415

Claims priority, application Italy Mar. 23, 1972

Term of patent 7 years

Int. Cl. D26—05

U.S. Cl. D48—20 A

FIG. 1 is a rear view of a lamp showing my new design, with the adjustable shielding element moved downwards to the front of the lamp;

FIG. 2 is a front view of the lamp in FIG. 1;

FIG. 3 is a side view of the lamp in FIG. 1;

FIG. 4 is a side view of the lamp with the adjustable shielding element moved into a vertical position;

FIG. 5 is a front view of the lamp in FIG. 4;

FIG. 6 is a rear view of the lamp in FIG. 4;

FIG. 7 is a rear view of the lamp with the adjustable shielding element moved into a horizontal position; and

FIG. 8 is a side view of the lamp in FIG. 7.

The characteristic features of my design reside in the adjustable shielding element.

I claim:

The ornamental design for a lamp, as shown and described.
